PAPER PACKAGE AND METHOD OF
MANUFACTURE

Ralph W. Schlienz, Harrington Park, N. J., assignor to Riegel Paper Corporation, New York, N. Y., a corporation of New Jersey

Application September 27, 1951, Serial No. 248,475

5 Claims. (Cl. 99—171)

1

This invention relates to paper packages and more particularly to envelopes or pouches, usually of small size, to contain pulverulent material or various small articles. It is customary to use such envelopes to contain individual servings of cocoa or chocolate powder used at fountains, and also such envelopes are used for confections, nuts and the like, and, in the hardware trades, to hold small hardware articles such as screws and washers.

In paper envelopes of this sort, as heretofore constructed, difficulty has been experienced in providing for a facile and quick opening of the package as well as an opening which is unobstructed so that entire contents, powdered material for example, may be quickly discharged from the envelope.

The principal object of the invention is to provide an envelope construction which overcomes these difficulties and which also can be manufactured easily on the present types of automatic envelope making and filling machines.

Another object of the invention is to provide, as a new article of manufacture, a paper stock web of suitable construction for feeding to an automatic envelope machine for the manufacture and filling of the improved package.

A further object of the invention is the provision of a novel method of making a paper envelope or pouch in quantity production from a continuous web of paper stock.

The invention will be understood from a consideration of the accompanying drawings and the following detailed description thereof.

In these drawings Fig. 1 is a diagrammatic, perspective view illustrating a step in the manufacture of the paper stock web which is also the first step in making the improved envelope.

Fig. 2 is a view showing the paper stock web formed by the uniting of the two web portions as illustrated in Fig. 1.

Fig. 3 is a view similar to Fig. 2 showing the two web portions partially folded.

Fig. 4 shows the folded web with a plurality of partially formed envelope sections.

Fig. 5 is a perspective view of a completed and filled envelope as it leaves the automatic filling machine.

Figs. 6, 7 and 8 are views in front elevation showing the steps in opening the improved envelope package.

Fig. 9 is a perspective view of a store counter rack holding a number of the filled envelope packages.

Fig. 10 is an enlarged fragmentary view of a detail.

2

Referring now to these drawings, the first step in making the improved package is to provide the paper stock web shown in Fig. 2 and indicated generally by reference number 1. This web consists of two portions of different width, for example, the narrower portion 2 and the wider portion 3 overlapped along one edge margin as indicated at 4, and having these overlapped margins adhesively secured together by a band of adhesive 5, which is narrower than the overlap and spaced from one edge thereof to leave a free margin 6.

Such a paper stock web may be made as indicated in Fig. 1. Here the wider web portion 3 is unwound from a magazine roll 7 and the narrower portion 2 is unwound from a magazine roll 8. The band 5, by which the web portions 2 and 3 are adhesively secured together is preferably formed by means of a thermoplastic adhesive, and furthermore, it is desirable to employ for web portions 2 and 3, a paper sheet material which is of a heat sealing type.

Accordingly, web portions 2 and 3 from magazine rolls 8 and 7 respectively, may be fed as shown in Fig. 1 to a heat sealing mechanism which comprises a heated and continuously rotated roller 9 cooperating with which is a support 10, for example, in the form of a horizontal rod, which may also be heated. The two overlapped webs are drawn between heating roller 9 and support 10 by any suitable means (not shown), and as the overlapped portions pass the heating roller 9, which is suitably disposed with respect to the margins of the paper, and which also is of the desired width, the two overlapped margins will be adhesively joined along the band 5. The paper stock web thus made may be wound upon a take-up roll and stored for later use, or the web may be fed directly to an automatic envelope making machine, or a combined envelope making and filling machine.

It will be understood that liquid adhesive or any appropriate and convenient type of adhesive may be used in place of the heat sealing type above described in causing the two web portions to be adhesively secured together along the band 5, but such adhesive should form a tearable seal as set forth in greater detail later on.

The next step in making the envelope is to fold the wider web portion 3 about that margin of the narrow web portion 2 which is proximate to the adhesive band 5. This is indicated in Fig. 3 where the two portions are shown in partially folded position. In Fig. 4 the folding of portions 2 and 3 flat against one another has been completed and the next step in the forma-

tion of a series of envelopes from the folded web is indicated. This next step consists in adhesively securing the two web portions or sections together crosswise by equally spaced bands, 11. This may be done by adhesive applied in any convenient manner, for example, prior to folding along the overlapped margin 4, if desired, or by heat sealing in a manner similar to the heat sealing of the webbed portions 2 and 3 together along the band 5. The folded web 1 is then cut into sections midway of each of the adhesive bands 11, as indicated by the dot and dash lines in Fig. 4, one of these sections being indicated by reference numeral 12.

When such a section 12 has been cut from the web, the improved envelope of the invention is ready for filling. This envelope is thus composed of the two web portions 2 and 3, which are adhesively secured together along the bottom by the band 5, and along each vertical side margin by one-half of the adhesive bands 11 leaving the upper margin unsealed. Such upper margin may thereupon be opened to receive the contents, for example, cocoa powder for making hot chocolate at fountains. After filling, the upper margin of the section 12 is closed as indicated at 13, preferably by heat sealing, although any convenient type of adhesive may be used.

The package of Fig. 5 has been filled through its bottom and in Fig. 6 the package is shown in upright position as it will be received by the user and manipulated in opening the package. Referring particularly to Figs. 5 and 6, the band of adhesive 5, being narrower than the width of the overlap 4 and also spaced from the edge of the wider web portion 3, leaves the exposed free margin 6, which may be used as a pull tab in opening the package. If the web portions 2 and 3 are secured together crosswise by heat sealing, the ends of the overlapped tab 6 will be simultaneously secured to the webbed portion 2 for its full width. If the webbed portions are secured together by adhesive applied prior to folding along the overlapped margin 4, the ends of the overlapped tab 6 will be separately secured to portion 2 at the opposite sides of the band 5 by adhesive in order to form a pocket behind the free margin or pull-tab 6 and to obtain a complete sealing of the package at that end.

Consequently, when the package is held, for example, in one hand and the tab 6 is grasped by the other to open the package, a pull on this tab will first cause the separation of the adhesively joined areas at the ends of the tab, as shown in Fig. 7. However, substantially simultaneously with this separation, the tab separates from the outer wall of the package along the adhesive band 5 and a continued pull upon tab 6 produces a complete separation, as shown in Fig. 8, of these formerly adhesively joined areas. In Fig. 7 the package appears somewhat narrower than in the other two figures, the intent being to show the curving effect on the package of the application of a pulling force to tab 6.

The complete separation of the overlapped portion 4 from the outside face of the envelope is accomplished by a single, quick pull or jerk on the tab 6 and leaves a full width opening for the discharge of the contents, that is, an opening which extends from the inner margin of the line of adhesive 11 on one side to the inner margin of line 11 of adhesive on the opposite side.

As previously mentioned, it is important that a type of adhesive be employed for band 5 (and at the opposite ends of tab 6) which will permit

the surfaces of the paper to be pulled apart, that is to say, the two paper surfaces should be secured together in the areas indicated by means of a tearable seal, a seal which is weaker than the paper itself so that the two layers or sheets will separate without tearing the paper when the tab 6 is pulled to open the package. This is readily accomplished with the use of a paper web of the heat sealing type for the web portions 2 and 3. Such a paper web may, for example, be made of bleached kraft paper having a thin coating of polyethylene. A coating of this material one-half a mil in thickness is satisfactory. It will be understood, however, that the paper web may be rendered heat sealing by other means such, for example, as by the use of appropriate heat sealing lacquers. Webs of other heat sealing cellulosic material, such as cellophane, may also be used.

The forming of a pocket behind the free margin or pull-tab 6 enables the packages to be attractively displayed. One manner of displaying the packages is shown in Figs. 9 and 10. As shown in these figures, a stand or easel 14, suitable for standing on a counter, has vertically-extending members 15 from which hooked portions 16 extend. These hooked portions may be inserted in the pocket formed behind the free margin or pull-tab 6 to display the packages in the manner shown.

It will be understood that the particulars of the invention described above may be modified in various ways without departing from the scope of the invention which is indicated in the appended claims.

I claim:

1. An envelope package comprising two sheets having their margins sealed together along three edges, one of said sheets being folded along the fourth edge of the package to overlap the outside margin of the other sheet and being adhesively secured thereto along a band of less width than the overlap, said band being spaced from the edge of the overlapped portion remote from the fold to leave a free central pull flap for opening the package, the ends of said pull flap being adhesively secured to said margins.

2. An envelope package comprising two sheets having their margins sealed together along three edges, one of said sheets being folded along the fourth edge of the package to overlap the outside margin of the other sheet and being adhesively secured thereto along a band of less width than the overlap, said band being spaced from the edge of the overlapped portion remote from the fold to leave a free central pull flap for opening the package.

3. A paper web stock for feeding to automatic envelope machines comprising two web portions of different widths, said portions being overlapped and adhesively joined together along a band of less width than said overlap, said band being spaced from the edge of the wider portion to leave an exposed, free margin projecting towards the opposite edge of the narrower portion.

4. The method of making paper web stock for feeding to automatic envelope machines which comprises overlapping the margins of two webs of different widths and adhesively joining the overlapped webs along a band of less width than the overlap and spaced from the proximate edge of the wider web to leave an exposed, free margin along said band projecting towards the opposite edge of the narrower web.

5. The method of making envelope packages

ready for filling which comprises overlapping the margins of two webs of different widths, adhesively joining the overlapped webs along a band of less width than the overlap and spaced from the proximate edge of the wider web to leave an exposed free margin along said band projecting towards the opposite edge of the narrower web, folding said web lengthwise with said exposed free margin on the outside, adhesively joining said webs crosswise at equally spaced bands, and cutting said folded web into sections midway of said bands.

RALPH W. SCHLIENZ.
